UNITED STATES PATENT OFFICE.

HARRY DIXSON, OF DES MOINES, IOWA, ASSIGNOR TO ROLSCREEN COMPANY, OF DES MOINES, IOWA.

ROLLING-WINDOW-SCREEN STRUCTURE.

Application filed August 16, 1926. Serial No. 129,566.

The object of my invention is to provide a rolling window screen structure of very simple and inexpensive construction.

In the manufacture and sale of rolling window screens of the type in which the screen is wound on a roller in a casing and is adapted to be withdrawn from and wound up into the casing, many difficult problems arise in connection with the installation of the screens in various kinds of window frames and casings.

At the present time, there is a great deal of building construction done in which it is the desire to avoid as far as possible the use of wood. In many instances, steel window sash and frames therefore are used in brick and plastic material buildings with a minimum use of wood. Frequently in such structures, the plaster is applied to the brick wall and finished around the window opening right up to the steel frame. The steel window sash are frequently hinged to the frame to swing outwardly and it is then necessary to install the screens so that they will be on the inside of the windows.

Where there is no wooden casing, such an installation involves a number of difficulties.

It is my purpose to provide a rolling window screen structure peculiarly adapted for use where there is no wooden frame.

It is my object in this connection to provide a casing for the rolling window screen, which for convenience and in order to correspond in terminology to the phrasing and names used in my co-pending application, Serial No. 29,960, filed May 13, 1925, I will call a box.

My device is intended for use with screens having enlarged portions at their edges, and I provide the box together with guides having slotted tubular portions adapted to receive the side edges of the screen.

It is my purpose to provide also channel-shaped receiving members or guide holders adapted to be mounted in the plastering or plastic finish when the same is applied, and to later detachably receive the guides to hold them by frictional engagement.

Another object is to provide in connection with such guide holding members and rolling screen box, members to receive the ends of the box and members for support-

ing the ends of the box in the holding member and adapted to be finished by painting or otherwise in the same manner as is the 55 plaster.

With these and other objects in view, my invention consists in the construction, arrangement and combination of the various parts of my rolling window screen structure, 60 whereby the objects contemplated are attained, as hereinafter more fully set forth, pointed out in my claims, and illustrated in the accompanying drawings, in which:

Figure 1 is a front elevation of a portion 65 of a building having a window opening equipped with a rolling window screen structure embodying my invention, the lower parts of the window being omitted.

Figure 2 is a detail, sectional view taken 70 on the line 2—2 of Figure 1.

Figure 3 is a detail, sectional view taken 75 on the line 3—3 of Figure 2.

Figure 4 is a sectional view taken on the line 4—4 of Figure 2.

Figure 5 is a detail, sectional view taken 75 on the line 5—5 of Figure 2.

Figure 6 is a perspective view of the parts of my rolling screen structure, portions thereof being broken away and parts being 80 omitted; and

Figure 7 is a sectional view of the guide holder, the view being somewhat enlarged and intended to illustrate the construction of the holder for affording the frictional 85 grip of the guide and the spread at the mouth of the holder.

In the accompanying drawings, I have used the reference numeral 10 to indicate generally the wall in which is provided a 90 window opening 11. I have shown my device installed in an opening having the steel window structure, including the metal frame 12 and the sash 13 hinged thereto.

At the upper part of the window open- 95 ing, there is provided in the wall a suitable recess 14 to receive the rolling window screen box 15. This box is the casing for the roller mechanism on which the screen 16 is wound. The box has the slot or longitudinal opening 17 through which the screen is drawn out.

In connection with this rolling screen, I use guides, each comprising a tubular por-

tion 18 with the slotted throat 19 at one side and with projecting flanges 20 at the other side. These flanges are preferably spot-welded together, so as to make each

5 guide a unit.

The tubular portion 18 terminates short of the upper ends of the flanges 20, as clearly shown in Figures 1 and 6. For holding the guides, I provide channel-shaped members.

10 These members comprise an angle 21 and an angle 22 arranged with flanges slightly spaced from each other and slightly converging toward their edges where they diverge, as shown in Figure 7, and with their other flanges lying in the same plane. One of the angles is substantially longer than the other, and the flanges which lie in the same plane, which are indicated at 21^a and 21^b, rest against a strip 23 to which they are spot-welded or otherwise secured.

20 The strip 23 extends to the upper end of the angle 22 and substantially above the angle 21. The upper portion of the strip 23 and the upper end of the angle 22 form parts 25 of a frame for receiving the upper end of the box 15 and the box 24 hereinafter more fully described.

The frame has also the angle side member 25 and angle top and bottom members 26 30 and 27 suitably connected together to make a rectangular receiving or holding member for the ends of the box. The ends of the box 15 are intended to be received in the upper portion of this holding member, which is 35 indicated generally by the reference character A, thus leaving below the box when it is installed, a substantial space enclosed by the angles 22, 25, 26 and 27 and the strip 23, which form side walls.

40 When the building is completed, this box holding member A and the channel-shaped guides formed as part thereof and projecting downwardly therefrom are placed in a window opening and the plaster 28 is put in 45 place overlying the flanges 21^a and 21^b, as shown in Figure 5, substantially flush with the outer edges of the angles 21 and 22 and the angle 27.

In the installation, the space between the 50 angles 21 and 22 may be filled with pasteboard or the like, which is intended to be removed when the time comes to install the guides.

Assuming that the box holding member A 55 and the channel receiving guides, which I have indicated generally by the reference character B have been installed during the plastering of the building, then when the time arrives to install the screen box and 60 guides, the box is placed in position with its ends received in the upper portions of the holder A.

It will be understood that the building is 65 provided at the top of the window opening with a suitable recess to receive the rolling

screen box 15. The guides are then slipped into position between the angles 21 and 22 with their upper portions projecting upwardly above the angle 21 to position immediately below the box 15, where they temporarily hold the box in position.

I provide a channel-shaped support 29, the side flanges of which are then inserted into the holder A with the support 29 just below the box 15 and with its lower end resting 75 on the angle 27 and with its outer face flush with the outer edges of the angles 25 and 22.

The outer face of the support 29 can then be painted over in the same manner as the walls. The projecting portions of the guides 80 are similarly painted.

The guides are held in place for frictional engagement by the angles 21 and 22.

In buildings of the kind mentioned, it is quite difficult to install the rolling window 85 screens in such a way that they can be readily removed. This problem I have solved by the present structure.

If it is desired to remove one of the boxes 15 for any reason as for instance to repair 90 the screen or roller, a knife or the like is inserted between the support 29 and the flange 27 and the support 29 is pulled out. The guides can then be pulled out of their receiving members. Thereafter, the box can be 95 slipped downwardly in the box holding member A with one end lower than the other end of the box, whereupon the box may be removed.

The lower surface of the box may be also 100 painted in the same way that the wall has been painted, so that when the entire device is installed only the tubular portions 18 of the guides project from the walls and all exposed surfaces of the screen structure are finished in the same way as the walls, so that 105 only a small part of the screen structure is visible and part of that exposed structure has the same finish as the walls.

I have thus provided a screen structure, 110 which can be conveniently installed in connection with plastic, brick or concrete walls in such a way as to detract to a minimum extent from the appearance of the structure and yet to permit the easy completion of the 115 installation of the rolling window screen and the quick and easy removal of the guides and boxes.

It will be understood that the guides are 120 located below the slot 17, so that when the parts are installed and the screen 16 is pulled downwardly, the side edges will be received in the guides, as shown in Figures 1 and 5.

The holders B will frictionally grip and 125 hold the guides and their receiving mouths are slightly flared as shown in Figure 7 to facilitate insertion of the guides.

Changes may be made in the details of 130 the construction and arrangement of the

parts of my improved rolling window screen structure without departing from the purposes and scope of my invention, and it is my intention to cover by my claims, any 5 such changes as may be reasonably included within their scope.

I claim as my invention:

1. A casing mounting including a recessed holder adapted to be embedded in plastic 10 material, said holder providing a recessed opening in the plastic material, a casing having one end received in one end of said holder and partially filling said opening and a support received in the holder for 15 filling the remaining portion of said opening and having one end of the casing resting thereon.

2. A casing mounting including a recessed holder adapted to be embedded in plastic 20 material, said holder providing a recessed opening in the plastic material, a casing having one end received in one end of said holder and partially filling said opening and a removable support received in the 25 holder for filling the remaining portion of said opening for supporting said casing with respect to the holder, said casing being adapted to be swung through the remaining portion of the opening when said support 30 is removed for installing the casing in or removing it from the holder.

3. A casing mounting comprising a recessed holder adapted to be embedded in plastic material for providing a recessed 35 opening therein, a casing adapted to have one end received in said holder, said holder being slightly wider and substantially longer than the end of said casing whereby said end can be moved longitudinally in the 40 holder and will partially fill the opening in the same and a support received in the holder for filling the remaining portion of said opening to prevent movement of the end of said casing relative to said holder.

45 4. A casing mounting comprising a recessed holder adapted to be embedded in a wall for providing a recessed opening therein, a casing adapted to have one end received in said opening, said holder being slightly wider and substantially longer than the end of said casing whereby said end can be moved longitudinally in the holder and 50 will partially fill the opening in the same, a support received in the holder for filling 55 the remaining portion of said opening to

prevent movement of the end of said casing relative to said holder, the surface of said support being substantially flush with the surface of the wall surrounding said holder and means adjacent one side of said holder 60 for retaining the support therein.

5. A casing mounting comprising a recessed holder adapted to be embedded in a wall for providing a recessed opening therein, a casing adapted to have one end received in said opening, said holder being slightly wider and substantially longer than the end of said casing whereby said end can be moved longitudinally in the holder and will partially fill the opening in the same, 65 a support received in the holder for filling the remaining portion of said opening to prevent movement of the end of said casing relative to said holder, the surface of said support being substantially flush with the 70 surface of the wall surrounding said holder.

6. A casing mounting including a recessed holder adapted to be embedded in plastic material, said holder providing a recessed opening in the plastic material, a casing 80 having one end received in one end of said holder and partially filling said opening and a support received in the holder for filling the remaining portion of said opening and having one end of the casing resting 85 thereon and means for frictionally retaining said support within the holder.

7. A casing mounting comprising a recessed holder adapted to be embedded in a wall for providing a recessed opening therein, a casing adapted to have one end received in said opening, said holder being slightly wider and substantially longer than the end of said casing whereby said end can be moved longitudinally in the holder and 90 will partially fill the opening in the same and means for filling the remaining portion of the opening in said holder and for retaining the casing within the holder.

8. A casing mounting including a holder 100 having a recessed opening of greater length than width, a casing having one end received in said opening and partially filling the same, and a support received in said opening for filling the remaining portion 105 of said opening and having one end of the casing resting thereon.

Des Moines, Iowa, July 29, 1926.

HARRY DIXSON.
